(57) **CLAIM**

The ornamental design for a trophy frame, as shown and described.

DESCRIPTION

FIG. 1 is a front perspective view of a first embodiment of the trophy frame of the present invention showing the Applicant's new design;

FIG. 2 is a front elevation view of the trophy frame of FIG. 1;

FIG. 3 is a rear elevation view of the trophy frame of FIG. 1;

FIG. 4 is a top plan view of the trophy frame of FIG. 1;

FIG. 5 is a bottom plan view of the trophy frame of FIG. 1;

FIG. 6 is a left side elevation view of the trophy frame of FIG. 1;

FIG. 7 is a right side elevation view of the trophy frame of FIG. 1;

FIG. 8 is a front perspective view of a second embodiment of the trophy frame of the present invention showing the Applicant's new design;

FIG. 9 is a front elevation view of the trophy frame of FIG. 8;

FIG. 10 is a rear elevation view of the trophy frame of FIG. 8;

FIG. 11 is a top plan view of the trophy frame of FIG. 8;

FIG. 12 is a bottom plan view of the trophy frame of FIG. 8;

FIG. 13 is a left side elevation view of the trophy frame of FIG. 8; and,

FIG. 14 is a right side elevation view of the trophy frame of FIG. 8.
